VALVE SEAT FORMING APPARATUS

Filed Feb. 10, 1945

FIG. 1

UNITED STATES PATENT OFFICE

2,503,404

VALVE SEAT FORMING APPARATUS

Wilbur L. Nelson, Chicago, Ill., assignor to Western Electric Company, Incorporated, New York, N. Y., a corporation of New York

Application February 10, 1945, Serial No. 577,321

4 Claims. (Cl. 78—1)

1

This invention relates to a valve seat forming apparatus and more particularly to an apparatus for forming cooperating surfaces of valves for crystal converters to properly seat movable valve members against their valve seats.

It is an object of the present invention to provide a simple and automatic apparatus for effectively and expeditiously seating valves on their associated valve seats.

In accordance with one embodiment of the invention as applied to an apparatus for forming cooperating surfaces of valves of the type disclosed in Patent No. 2,456,305, issued December 14, 1948, to W. L. Nelson, on their associated valve seats, an apparatus is provided for holding the crystal converter unit in a fixed position to have the valve reciprocated by a rotatable and reciprocatable shaft having chuck thereon for holding the valve stem. A motor, operable through a speed reducer to drive a sleeve, also drives a wheel having cam surfaces thereon for closing a switch to energize a solenoid repeatedly in timed relation to the rotation of the sleeve. The rotatable sleeve is recessed to receive an end of a shaft and has a cam therein adapted to cooperate with a pin on the shaft whereby rotation is imparted to the shaft and chuck carried thereby intermittently when the valve is out of engagement with its valve seat, thus to repeatedly bump the valve against opposing valve seats while the valve is not rotating and to rotate the valve during the reciprocating movement, but not during the bumping portion of the reciprocation.

A complete understanding of the invention may be had by reference to the following detailed description when considered in conjunction with the accompanying drawing, wherein

Fig. 1 is a plan view of an apparatus made in accordance with the present invention;

Fig. 2 is an enlarged fragmentary view of the driving sleeve and cam therein;

Fig. 3 is a transverse sectional view taken substantially along the line 3—3 of Fig. 2 in the direction of the arrows;

Fig. 4 is an enlarged fragmentary view taken substantially along the line 4—4 of Fig. 1 in the direction of the arrows and showing the wheel having the cam surfaces thereon for closing the solenoid energizing switch; and

Fig. 5 is an enlarged fragmentary longitudinal sectional view taken substantially along the line 5—5 of Fig. 1 in the direction of the arrows showing some details of the valve and valve seats in the crystal converter.

Referring now to the drawings, wherein like

2

reference characters designate the same parts throughout the several views, one form of the apparatus is shown mounted on a base 8, on which there is supported a suitable tail stock chuck or vise 9, adapted to hold a crystal converter unit 10 in a position where its valve stem 11 may be gripped by a chuck 12. The crystal converter unit 10 includes a valve member 13 slidable in a tubular element 14 and having two seating faces 15 and 16, which are adapted to seat against a valve seat 17 and a valve seat 18, respectively. The valve seat 17 is formed as a shoulder of the tubular element 14 and the valve seat 18 is formed as a shoulder of a coaxially positioned tubular element 19.

In the operation of the apparatus, the seating faces 15 and 16 are bumped or hammered against the valve seats 17 and 18 while not rotating on the axis of the valve member, but the valve member is rotated intermittently to present different surfaces of the faces 15 and 16 in association with different areas of the valve seats 17 and 18, thus to insure that a tight fit is effected between the seating faces of the valve member and its associated valve seats.

Suitably mounted upon the base 8 is a driving motor 25 for driving a shaft 26 extending into a speed reducer 27, which has an output shaft 28. The output shaft 28 of the speed reducer has 30 mounted upon it a cam wheel 29, having a plurality of cam bumps 30 thereon (Fig. 4) adapted to actuate an arm 31, which, through a pin 32, serves to close a switch 33. The switch 33 controls the supply of power to a solenoid 34, having a core 35, which carries an actuator arm 36, in position to engage a collar 37 on a chuck driving shaft 38. The chuck driving shaft 38 has the chuck 12 fixed at its right end and is slidably and rotatably journaled in a pair of bearing members 39 and 40, which extend upwardly from the base 8. Interposed between the bearing member 40 and the collar 37 is a compression spring 41, which urges the chuck driving shaft 38 to the right (Fig. 1) and normally tends to force the seating face 16 against the valve seat 18. In this operation, the spring 41 is aided by a spring 42 forming a part of the converter unit 10.

Adjacent its left end, the chuck driving shaft 38 extends into a sleeve 43 attached to the end 50 of the shaft 28 and cam wheel 29 in any suitable manner. The chuck driving shaft 38 is slidable within the sleeve 43 and carries a cam follower pin 44, which extends radially on opposite sides of the shaft 38 into cam slots 45 and 46 formed in the walls of the sleeve 43 and diametrically

opposed one to another. The cam slots 45 and 46 are of exactly the same shape and are generally of rectangular shape and each have two rounded protuberances 47 and 48 adjacent their mid portions, the inner surfaces of which are spaced apart just sufficiently to permit the pin 44 to pass between them when the shaft 38 is reciprocated. The portions of the cam slots 45 and 46 removed from the rounded protuberances 47 and 48 are provided so that, although the motor 25 and speed reducer 27 drive the sleeve 43 at a constant rate of speed, the chuck driving shaft 38 will not be driven by the sleeve 43 at a constant rate of speed due to the fact that the solenoid 34 will be intermittently energized by switch 33, and, when the solenoid is energized, the shaft 38 will be moved to its lefthand position, as shown in Fig. 1, and as it approaches the limit of its travel to bump the seating face 15 against the valve seat 17, the pin 44 will be free of the protuberances 47 and 48 and the valve will be bumped against the valve seat while no rotation is being imparted to it. Similarly, when the solenoid 34 is deenergized by the opening of switch 33, the spring 41, in cooperation with spring 42, will shift the pin 44 from its lefthand position, as shown in Fig. 1, over to an extreme right hand position, as shown by the dotted line in Fig. 1. Thus, when the valve member 13 is carried to a position where its seating face 16 engages the valve seat 18, no rotation will be imparted to the seat 18 valve while it is in engagement with the seat 18. The contour of the cam bumps 30 is so arranged that the switch 33 will be closed for an interval of sufficiently short duration that no rotary motion will be imparted to the valve while its seating faces 15 and 16 are in engagement with their respective valve seats 17 and 18. Obviously, while the shaft 38 is reciprocating, either under the influence of the solenoid 34 or under the influence of the springs 41 and 42, the shaft will be driven at a faster rate of speed than the speed of rotation of the sleeve 43 due to the fact that the pin 44 will ride up on the rounded protuberances 47 and 48 in passing between them, depending upon the direction of rotation of the sleeve 43.

What is claimed is:

1. An apparatus for forming cooperating seating surfaces on a valve member and on a valve seat comprising a sleeve having a cam shaped slot therein, means for rotating said sleeve, a shaft having a cam follower engaging said slot, said cam shaped slot having a cam rise intermediate axially extending end portions of the slot, means for reciprocating said shaft whereby a rotary motion is imparted to said shaft intermediate the ends of its reciprocatory movement, and means for attaching said valve member to said shaft.

2. In an apparatus for forming opposed sur-

faces on a valve and on cooperating opposed seats for said valve, a valve engaging member, a spring for urging said member toward one seat engagement, a solenoid for moving the member toward the opposite seat engagement, a continuously driven sleeve, a shaft extending into said sleeve, means connecting said shaft to said member, means driven by said sleeve for causing actuation of the solenoid, a shaft driving pin on said shaft, and a pair of driving surfaces on said sleeve for engagement with said pin to rotate the shaft intermediate the extremes of its reciprocation to thereby rotate said member.

3. An apparatus for forming cooperating seating surfaces on a valve member and on a valve seat comprising means connectible to said valve member, means for imparting reciprocation to the means connectible to the valve member, a rotary driving means, and means of connection between the driving means and means connectible to the valve member including a sleeve having a cam shaped slot therein, and a shaft having a cam follower engaging said slot, said cam shaped slot having a cam rise intermediate axially extending end portions of the slot whereby rotary motion will be transmitted to the valve member intermediate the ends of its reciprocatory movement.

4. An apparatus for forming cooperating seating surfaces on a valve member and on a valve seat comprising means connectible to said valve member, means for imparting reciprocation to the means connectible to the valve member, a rotary driving means, a switch actuating cam member driven by said driving means, a switch operated by said cam member for causing actuation of the reciprocation imparting means, and means of connection between the driving means and means connectible to the valve member including a sleeve having a cam shaped slot therein, and a shaft having a cam follower engaging said slot, said cam shaped slot having a cam rise intermediate axially extending end portions of the slot whereby rotary motion will be transmitted to the valve member intermediate the ends of its reciprocatory movement.
